United States Patent

Des. 235,404
Patented June 17, 1975

235,404

FOOD MOLD

James B. Swett, Barrington, R.I., and Richard A. Boucher,
Northboro, Mass., assignors to Dart Industries Inc., Los
Angeles, Calif.

Filed Jan. 24, 1974, Ser. No. 436,324

Term of patent 14 years

Int. Cl. D7—02

U.S. Cl. D7—43

FIG. 1

FIG. 2

FIG. 3

FIG. 4

FIG. 1 is an exploded top perspective view of a food mold showing our new design;

FIG. 2 is an assembled elevational view thereof;

FIG. 3 is a top plan view thereof with the planar closure removed; and

FIG. 4 is a bottom plan view thereof.

We claim:

The ornamental design for a food mold, substantially as shown.
